(57) **CLAIM**

The ornamental design for a bowling motif tea pot/kettle, as shown and described.

DESCRIPTION

FIG. 1 is a perspective view of the bowling motif tea pot/kettle showing our new design;

FIG. 2 is a left side view thereof which is also a mirror image of the right side thereof;

FIG. 3 is a front perspective view of a second embodiment of our new design with the kettle portion removed for ease of illustration. The kettle portion being identical in both embodiments.

FIG. 4 is a bottom plan view of both embodiments thereof;

FIG. 5 is a top view thereof;

FIG. 6 is a front-end view thereof; and,

FIG. 7 is a back-end view thereof.
